FIG. 3.

UNITED STATES PATENT OFFICE.

AUGUST F. BEHRMAN, OF BUENA VISTA, COLORADO.

DUMPING-CART.

SPECIFICATION forming part of Letters Patent No. 447,442, dated March 3, 1891.

Application filed September 30, 1890. Serial No. 366,671. (No model.)

To all whom it may concern:

Be it known that I, AUGUST F. BEHRMAN, a citizen of the United States, residing at Buena Vista, in the county of Chaffee and State of Colorado, have invented a new and useful Dumping-Cart, of which the following is a specification.

My invention relates to improvements in dump-carts which are provided with suitable mechanism whereby the end-gate of the cart may be readily opened at the front of the cart simultaneously with the dumping of the cart; and it consists in certain features of novelty to be hereinafter described and claimed.

In the accompanying drawings, Figure 1 is a side view of my improved dump-cart. Fig. 2 is a bottom view. Fig. 3 is a longitudinal sectional view. Fig. 4 is an end view.

1 represents the body of the cart, which is provided with an axle 2 and wheels 3.

4 is a swinging frame pivoted at each end of the axle and extending to the front of the cart, where it is provided with a pivoted support 5 to hold the cart in a horizontal position and off of the horse when at rest. This swinging frame is supported to the cart-body by mechanism presently to be described.

6 is the end-gate, hung at top by means of laterally-extending pins 7, projecting from braces 8 and being received by rearwardly-extending open bearings 9 at the top of the rear end of the cart. These pins or pivots 7 are flattened on a plane transverse to that 35 of the end-gate 6, so that when the gate is thrown up into vertical position it may be withdrawn from its bearing.

At each side of the body 6 are secured rearwardly-projecting hooks 10, that are engaged 40 by the hooks 11 when the gate is shut, said hooks projecting forwardly from a rock-shaft 12, journaled in bearings 13 in the braces 8 and in bearings 14 between the ends of the gate, said rock-shaft being operated by a 45 downwardly-extending lever 15. The upwardly-extending end 15^a of the lever 15 is thrown outwardly by a spring 16, thus causing the said hooks to normally engage each other and lock the end-gate to the body 6. 50 The means for locking the end-gate to the body thus described is the same as that shown, described, and claimed in my patent, No.

431,318, dated July 1, 1890, and hence I do not lay claim thereto in this application.

At the rear of the bottom of the body 6 is 55 a cross-piece 17, through the outwardly-extending ends of which pass the strengthening-braces 18, formed with the bearings 9 and screw-threaded at their lower ends to receive nuts 19. Longitudinally of the bottom of the 60 body and midway between its sides is a longitudinally-movable rod 20, guided in bearings 21 and 22, formed in the axle and the rear cross-bar, respectively, said rod being projected normally forward by means of a 65 coiled spring 23, having bearing at one end at 24 and engaging a collar 25 at the other end, said collar forming a part of said rod. Inasmuch as said spring projects said rod 20 normally forward, it will also be evident that 70 its rear end, which is received by a recess 26 in the lower edge of the end-gate, is normally held out of contact with the lever 15 of said end-gate. The forward end of said rod 20 is bent downwardly and formed into a bolt 27, 75 received by bearing 28 at the front end of the bottom of the body and normally engaging a recess 29, formed in the lower side of the front bar of the frame 4, thus locking the body normally to said frame. To the rear of 80 the bearing for said bolt and formed oppositely in the top and bottom thereof are notches or recesses 30, with which engage the forks of the bifurcated end 31 of the bell-crank lever 32, pivoted, as at 33, to the front 85 cross-bar 34 of the body 1. The front end of the bell-crank lever 32 is engaged by the lower end of a lever 35, pivoted at 36 within a boxing 37, set into the front end of the body. The front end of the bolt 27 of said 90 rod 20 is beveled downwardly and rearwardly, so that after the body 1 has been dumped the bolt will be sprung inwardly by reason of the front bar of the frame 4 being engaged thereby, so that when the body is in position 95 the bolt will be sprung into its recess.

At one end of the end-gate is a curved guide 38, extending upwardly from a strip 39. Said guide is provided with a groove 40 to receive a cord or cable 41, secured to the 100 rear end of said guide at 42 in a suitable manner, said cord or cable extending forwardly along one side of the body and over a pulley 43, journaled in a boxing or housing 44,

secured to the body and downwardly to the frame 4, where it is connected at one side at 46.

From the above description, in connection with the drawings, it will be evident that 5 when the lever 35 is moved in a proper direction, so as to throw the rear end of the bell-crank lever rearwardly, the bolt 27 will be withdrawn from engagement with the frame 4, thus permitting the dumping of the body. 10 Automatically with the dumping of the body the rear end of said bolt-rod will be brought into engagement with the lever 15, thus disengaging the hooks 10 and the lever, the end-gate being thereby released and drawn up 15 into a horizontal position by the action of the cable or cord 41.

By this construction of dumping-carts I obtain a very practical and simple device, which will enable a great saving of labor, especially when used on railroads. 20

Having described my invention, what I claim is—

1. In a dump-cart, the combination of the axle supporting the body, the pivoted thill-frame having a cross-bar, the longitudinally-movable spring-actuated rod having a bolt engaging a recess in said cross-bar, the end-gate having a rock-shaft provided with catches engaging hooks upon the cart-body, and a 25 downward-extending lever or handle lying in the path of the longitudinally-movable rod, and a spring pressing against an upward extension of said lever or handle, substantially as and for the purpose set forth.

2. In a dump-cart, the combination of the 35 body mounted upon the axle, the hinged end-gate provided with a rock-shaft, the locking-catches engaging hooks upon the cart-body, a spring - actuated lever - handle, the longitudinally-sliding rod adapted to engage the 40 lever-handle and terminating at its front end in a beveled bolt engaging a recess in a cross-bar of the thill-frame, a bell-crank lever having a forked arm engaging recesses in the longitudinally-sliding rod, and a lever pivoted upon the front end of the cart-body and adapted to engage the forwardly-extending arm of the bell-crank lever, substantially as 45 set forth.

3. In a dump-cart, the combination, with 50 the body of the hinged end-gate having the strip 39, provided with a curved guide 38, having groove 40, of the thill-frame pivoted upon the axle, a guide-pulley mounted upon the side of the cart-body, and a rope or equivalent 55 41, attached to the curved guide 38, and passing over the guide-pulley to the thill-frame, where it is made fast, substantially as and for the purpose set forth.

In testimony that I claim the foregoing as 60 my own I have hereto affixed my signature in presence of two witnesses.

AUGUST F. BEIRMAN.
